Primary Examiner — John M Otte

(57) **CLAIM**

The ornamental design for a display screen or portion thereof with animated graphical user interface as shown and described.

DESCRIPTION

1. Display screen or portion thereof with animated graphical user interface

1.1 : Front

1.2 : Change State View 1

1.3 : Change State View 2

1.4 : Change State View 3

1.5 : Change State View 4

1.6 : Change State View 5

The key features of the design lie in the animated graphical user interface; reproduction 1.1 is the first image in a sequence; reproduction 1.2 is the second image thereof; reproduction 1.3 is the third image thereof; reproduction 1.4 is the fourth image thereof; reproduction 1.5 is the fifth image thereof; reproduction 1.6 is the sixth image thereof; the process or period in which one image transitions to another image forms no part of the claimed design; the broken line in the reproductions showing a display screen or a portion thereof is for the purpose of illustrating environment and forms no part of the claimed design.

1 Claim, 6 Drawing Sheets
